US00D564461S

(12) **United States Design Patent** (10) **Patent No.:** **US D564,461 S**
Kim et al. (45) **Date of Patent:** **** Mar. 18, 2008**

(54) **LIGHT EMITTING DIODE (LED)**

(75) Inventors: **Min Hong Kim**, Gyeonggi-do (KR);
Do Choul Woo, Seoul (KR); **Mi Gyeong Go**, Gyeonggi-do (KR); **Chung Hoon Lee**, Gyeonggi-do (KR)

(73) Assignee: **Seoul Semiconductor Co. Ltd.**, Seoul (KR)

(**) Term: **14 Years**

(21) Appl. No.: **29/263,716**

(22) Filed: **Jul. 28, 2006**

(30) **Foreign Application Priority Data**

Mar. 29, 2006 (KR) 30-2006-0011613

(51) **LOC (8) Cl.** **13-03**

(52) **U.S. Cl.** **D13/180**

(57) **CLAIM**

The ornamental design for light emitting diode (LED), as shown and described.

DESCRIPTION

FIG. 1 is a perspective view of a light emitting diode (LED) showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 4 Drawing Sheets
